UNITED STATES PATENT OFFICE.

LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

WICK.

1,403,010.

Specification of Letters Patent. Patented Jan. 10, 1922.

Application filed March 23, 1918. Serial No. 224,208.

To all whom it may concern:

Be it known that I, LEE S. CHADWICK, a citizen of the United States, residing at East Cleveland, in the county of Cuyahoga and State of Ohio, have invented a certain new and useful Improvement in Wicks, of which the following is a full, clear, and exact description, reference being had to the accompanying drawings.

10 This invention relates to improvements in wicks for oil stoves, lamps, and the like.

Considerable difficulty is experienced by users in re-wicking oil stoves and lamps, especially wherein tubular wicks are employed 15 for the reason that unless the adjustment of the wick is very accurate, uneven and smoky flames result, and without some means for definitely locating the wick within the burner, the average user is unable to 20 obtain the proper adjustment.

The objects of this invention are to provide an arrangement of wick and wick carrier that permits relative adjustment between the wick and carrier and obviates the 25 above difficulty; that affords cheap and convenient renewal of the wick; that adds no appreciable expense to the wick; and that is so simple and convenient of manipulation that it may be placed in unskilled and un- 30 familiar hands with assurance that the proper adjustment of the wick within the stove or lamp will be obtained.

The invention consists essentially in providing a carrier for the wick having some 35 sort of positioning or attaching means together with a wick having positioning or attaching means for cooperation with those of the carrier wherefore a definite relation between the wick and carrier is bound to 40 result, one of the elements preferably having a series of positioning or attaching means enabling the other to be adjusted with respect to the former from time to time.

45 In the drawing accompanying and forming a part hereof, Fig. 1 is a perspective view of a tubular wick and carrier attached in accordance with my invention; Fig. 2 is a similar view of the parts in the act of 50 inserting the wick into the carrier; Fig. 3 is a fragmentary perspective view showing the cooperating positioning and attaching means of the carrier and the wick; and Fig.

4 is an enlarged sectional detail through the positioning and attaching means of the wick 55 and carrier.

In the present embodiment the wick 1 is provided with a series of circumferentially arranged rows of grommets or eyelets 2. The carrier, designated 3, consists of a sheet 60 metal tube having projections 4 turned inward at its upper edge and barbs 5 incline inwardly from its lower edge, the projections serving to maintain the wick in contact with the tube of the burner wherewith 65 the wick is designed for use in accordance with a common and well known practice, while the barbs 5 serve an additional purpose of positively grasping the wick between itself and the burning tube throughout the 70 entire circumference of the wick so that when the carrier is moved by the wick raising and lowering means the wick will move alike throughout its circumference. The 75 carrier is provided with the usual perforations 6 serving the combined purpose of admitting oil to the wick and providing means for cooperation with the wick raising and lowering mechanism.

Shown as near its lower end the carrier 80 is provided with positioning and attaching means 10, preferably formed by punching inward a plurality of prongs 11 that possess the resiliency of the material whereof the carrier is formed. The grommets or eyelets 2 of the wick are adapted to be pressed over the prongs 11 and cooperate therewith in the nature of a snap fastener so that the wick may be readily attached to and detached from the carrier. 85

In attaching the wick to the carrier it is convenient to flatten out the wick and then fold it longitudinally upon itself and insert it through the carrier, as indicated in Fig. 2. Then by placing a finger upon the side of 90 the folded wick opposite one of its attaching means, said means may be snapped over one of the cooperating means of the carrier. By unfolding the wick, the next attaching means thereof may be applied to the corresponding attaching means of the carrier; and then by opening the wick and placing the fingers inside, the remaining attaching means of the wick and holder may be conveniently brought into engagement. There- 10 after the wick may be pressed out against

the carrier into the condition illustrated in Fig. 1, when it is ready to be introduced into the burner of the stove or lamp.

From the construction hereinbefore described it will be seen that, when the wick and carrier are assembled the upper edge of the wick bears a definite relation to the carrier; and it must follow, therefore, that when the carrier is placed within the burner, the wick will properly be adjusted for use. After the wick has been consumed to a given extent, the carrier and the wick may be removed from the burner and the wick readjusted with respect to the carrier by moving it up to its next row of attaching means so that the life of the wick is very materially prolonged. This is a decided advantage over the prevailing types of wick and wick carriers where the wick and wick carrier are permanently connected and therefore incapable of relative adjustment, and, in addition, making it necessary to discard both wick and carrier. With my invention, new wicks may be supplied for use with old carriers, the latter being practically indestructible.

Having thus described my invention, what I claim is:—

1. The combination of a wick and carrier, the carrier having attaching means, and attaching devices carried by the wick for separable connection with the attaching means of the carrier.

2. The combination of a wick and carrier,

one having attaching means and the other 35 a series of attaching devices for separable connection with the attaching means of the first, thereby permitting adjustment between the wick and carrier.

3. The combination of a wick and carrier, 40 one having a positioning means, and the other a series of positioning devices for interengagement with the positioning means of the first.

4. The combination of a wick and carrier, 45 one having a set of attaching means, and the other a series of sets of means for cooperation with the attaching means of the first.

5. The combination of a tubular wick and a cylindrical wick carrier, the carrier having 50 a circumferentially disposed row of attaching means, and the wick having a series of circumferentially disposed rows of attaching means for cooperation with those of the carrier.

6. The combination of a tubular wick and a cylindrical carrier therefor having inwardly directed projections at its upper end and inwardly directed barbs at its lower end, the carrier being provided with inwardly directed entering elements intermediate its ends, and the wick having grommets for the reception of the entering elements of the carrier.

In testimony whereof, I hereunto affix my 65 signature.

LEE S. CHADWICK.
